Primary Examiner — Darlington Ly

Assistant Examiner — Katherine A Holbrow

(74) Attorney, Agent, or Firm — Botos Churchill IP Law LLP

(57) **CLAIM**

The ornamental design for a display screen with icon, as shown and described.

DESCRIPTION

The sole FIGURE is a front view of a display screen with icon showing our new design.

The broken lines of uneven length show the display screen and form no part of the claimed design.

1 Claim, 1 Drawing Sheet(56)
